Application November 10, 1937, Serial No. 173,831

11 Claims. (Cl. 12—33)

This invention relates to improvements in machines for use in applying pressure to shoe bottoms and is illustrated herein as embodied in an apparatus adapted more particularly for use in cement attaching soles to shoes.

In shoes which have their outsoles attached by cement the heel portion of the outsole is usually left unattached to the shoe bottom in the same manner as in welt shoes and this heel portion is thereafter secured to the shoe bottom by nails after which the heel or the heel base is attached to the heel seat portion of the sole by additional nails. In attaching the heel end of the sole to the shoe by nails the edge portion of the sole is forced tightly against the heel portion of the shoe bottom and, since the nails are clinched on the inside of the shoe, this edge portion is maintained permanently in such position. The heel attaching nails likewise cause the edge of the heel or heel base to be forced into close fitting relation with the edge of the sole and they hold these edges permanently in that position so that, after the sole has dried out, no openings or spaces will appear between these edges such as might result if no nails were used owing to differences in the firmness of the leather materials at the heel seat portion of the shoe which cause the leather to react more in some places than in others and tend to return to its original uncom- 30 pressed condition when the heel attaching pressure is relieved.

When, however, the heel portion of the sole is to be attached to the shoe bottom by cement alone and when, in addition, as is the case with many shoes manufactured today, the heel or heel base is also to be attached to the heel seat portion of the sole by cement alone, a problem arises with respect to securing and maintaining a close fitting relation between the edges of these parts 40 at the heel end of the shoe because, in such cases, no nails will be present to maintain said edges permanently in the close fitting contact they had while under heel-attaching pressure.

Accordingly, unless some means is provided for overcoming these difficulties, shoes having both the heel seat portions of their outsoles and their heels or heel bases attached by cement alone to produce a so-called nailless heel seat are apt to have spaces or openings appear between the sole 50 edge and the shoe bottom at the heel portion of the shoe, or between the sole edge and the edge of the heel or heel base.

Objects of the present invention are to provide improved apparatus for use in applying pressure to soles and shoes including the entire heel

portions thereof, and to provide improved means for operating on the heel seat portions of soles during the application of pressure thereto in order to eliminate the difficulties above referred to in constructions in which both the heel seat portion of the sole and the heel or heel base are to be attached respectively to the shoe and the sole by cement alone.

To the attainment of these objects and in accordance with one of its features, the invention 10 provides an improved pad box structure constructed and arranged to apply pressure to the entire areas of a sole and a shoe bottom and simultaneously to mold or conform the heel portion of the sole to the shape of the attaching 15 face of a heel or heel base. As illustrated herein, the pad box has a yieldable pad provided with a sole and shoe receiving surface which is deformable under pressure and is arranged to extend over the entire bottom area of the largest shoe 20 to be operated upon. A smooth surface for engaging the sole is provided by a continuous flexible blanket or cover, preferably of resilient material, which can be deformed with the yieldable 25 surface of the pad during the pressure applying operation.

The improved means referred to for operating on the heel portion of the sole comprises, as herein illustrated, a rigid plate interposed between the yieldable pad and the flexible cover and constructed and arranged to mold or conform the heel seat portion of the sole to the shape of the attaching face of a heel or heel base while sole attaching pressure is being applied to the sole and shoe, thereby producing a smooth, even 35 compressed edge on the heel seat portion of the sole which could not be obtained by pressure from a yieldable pad alone owing to hard and soft spots in the material of the sole. As illustrated, the rigid plate has a floating contact with 40 the operating surface of the pad so that it is free to tip or be moved heightwise of the shoe with said surface as the pad and cover are deformed under the pressure applied to the shoe and sole.

The operating surface of the plate is concave 45 and corresponds in shape to the attaching face of a heel or heel base so that, as the pressure is applied, the heel seat portion of the sole will be molded or conformed to the shape of said attaching face. This insures that the edge of 50 the sole will be compressed evenly and without high and low places which would cause open spaces between the sole edge and shoe or between the sole edge and the edge of the heel or heel base after the heel attaching pressure was 55

relieved in cases where cement alone was used to attach the sole to the shoe bottom and to attach the heel or heel base to the sole.

In accordance with another feature of the invention, the conforming plate is adjustable longitudinally of the pad box, thereby permitting the plate to be readily positioned for operating on soles of different lengths. As illustrated herein, the adjustment of the plate is effected by manually operated means whereby the plate may be moved predetermined distances lengthwise of the pad without interfering with its freely movable floating relation to the pad or the pad cover. Moreover, the longitudinal adjustment may be accomplished, in accordance with the present invention, without displacing the flexible pad cover overlapping the plate or interfering with the operation of the pad or mechanisms associated therewith.

Still another feature of the invention comprises an improved arrangement for insuring that the heel end of the sole will always be properly positioned on the pad relatively to the shoe. Since the flexible cover overlaps the concave surface of the rigid heel conforming plate, the cover may, under continual use, gradually conform to the concave shape of said surface and thus render it difficult for heel positioning gages which are arranged to operate in a fixed or predetermined plane to engage the edge face of a sole located in this concave or cupped surface. This difficulty is overcome in the present construction by causing the operative ends of positioning gages for locating the heel end of the sole relatively to the shoe to rest by their own weight or gravity on the surface of the pad cover and to ride or slide on this surface during their operative movement into engagement with the sole. In this way there is no opportunity for the gages to ride over the top of a sole located in a concave depression at the heel end of the pad and consequently danger of the gages failing to engage and position the sole is eliminated.

With the above and other objects and features in view, the invention will now be described in connection with the accompanying drawings and will thereafter be pointed out in the claims.

In the drawings,

Fig. 8 is a longitudinal sectional view taken on the line VIII—VIII of Fig. 6;

Fig. 9 is a perspective view of the sole heel gages operating on the heel end of a sole resting on a flexible cover which extends over a pad in the pad box; and

Fig. 10 is a perspective view of the sole conforming means and the mechanism for supporting and adjusting said means.

The invention is illustrated herein as embodied

in a pad box for use in a cement sole attaching machine of the type disclosed in Letters Patent of the United States No. 2,047,185, granted July 14, 1936, on an application filed in the name of Milton H. Ballard et al., this pad box being modified in the manner disclosed in Letters Patent of the United States No. 2,005,755, granted June 25, 1935, on an application filed in the name of Francis J. Better, to adapt it more particularly for operating on large size shoes, such as men's shoes. As disclosed in the Ballard et al. patent, the pad box is secured by screws 12 to a radially projecting portion 13 of a supporting shelf or table which forms a portion of a rotary turret on the cement sole attaching machine. The pad box comprises a fixed casting 14 for supporting the rear portion of a yieldable pad 16 and a movable casting 18 arranged to swing about a center 20 for supporting the forward portion of the pad and for positioning this portion at a proper angle for the shape of the shoe being operated upon. As herein illustrated, the yieldable pad 16 comprises a hollow bladder, preferably of rubber, filled with fluid such as water, and it extends to the rear or right-hand end of the fixed casting 14 of the pad box, as shown in Fig. 8. The movable casting 18 carries sole and shoe positioning gages, indicated generally by the numeral 22 and being of substantially the same construction as those disclosed in United States Letters Patent No. 2,063,041, granted December 8, 1936, on an application filed in the name of Lloyd G. Knowles.

The rear or right-hand end of the pad box as viewed in Fig. 1, is provided at its opposite sides with vertical guideways 24 in which is adjustably mounted a slide member 26 the upper end of which projects horizontally to form a supporting plate or table 28 upon which is mounted gage mechanism for relatively locating the heel ends of a sole and shoe on the pad, the plate 28 also supporting mechanism forming a part of the present invention for conforming the heel portion of a sole to the shape of the attaching face of a heel or heel base during the application of pressure to the sole and shoe. The slide 26 is adjusted in the guideways 24 and is maintained in adjusted position by a screw 30 (Figs. 3 and 8) threaded into a horizontally projecting lug 32 formed on the lower end of the slide, the screw being secured by a lock nut 34 in a fixed bracket 36 fastened by screws 38 to the casting 14 of the pad box. In adjusting the slide 26 heightwise of the pad box the lock nut 34 is loosened and the screw 30 is turned until the proper heightwise position of the slide is attained, after which the lock nut is made fast again against the fixed bracket 36. The heightwise position of the slide 26 is determined, in a manner to be hereinafter explained, in accordance with the amount that the flexible pad 16 is distorted under the sole attaching pressure. It will be seen from the above that the slide 26 and the mechanism carried thereby are fixed against movement heightwise of the shoe during the operation of the machine but that they are capable of adjustment heightwise of the shoe.

The horizontal projection 28 on the slide 26 carries sole and shoe positioning mechanism with which a pad box of the present type is provided for relatively positioning the heel ends of a sole and shoe on the pad, this mechanism comprising, as fully disclosed in the Better patent referred to, a plurality of substantially horizontal members 40 (Figs. 1, 3 and 8) which carry a pair of

transverse slides 42, 44 adapted to operate, respectively, by means of inclined slot and roll arrangements 46 (Fig. 6) and 47 (Fig. 4), a pair of pivoted shoe positioning gages 48 and a pair 5 of pivoted sole positioning gages, indicated generally by the numeral 50. The gages of each pair are interconnected respectively by gear segments 52, 53 for equal and opposite swinging movement toward and away from a shoe and sole 10 on the pad. The transverse slide 44, which operates the sole positioning gages 50, is caused to move inwardly of the machine away from the operator by a tension spring 54 (Fig. 8) when a roll 60 (Fig. 6) is removed from engagement with the end of the slide by treadle operated mechanism including a bell crank lever 62 operating the roll 60 through a link 64, this lever 62 being also arranged to operate the forepart gage mechanism 22 through a second link 66 which connects it to said mechanism.

The transverse slide 42 for operating the shoe heel gages 48 is actuated through the movement of a swinging frame member 68 (Figs. 1 and 3) which is arranged to be moved manually from a rearwardly inclined, inoperative position into a substantially vertical, operative position by a handle 70. The slide 42 is connected by a rod 72 to a pivoted arm 74 (Fig. 3) on the swinging frame 68 so that forward movement of the 15 swinging frame causes the slide 42 to be moved forwardly toward the operator and, by reason of the roll and inclined slot arrangement previously referred to, to move the inter-connected shoe gages 48 into engagement with the shoe 20 resting on the sole.

As shown in Figs. 1 and 8, the several gage supporting members 40 are arranged for pivotal movement about a horizontal pin 76 so that the operative ends of the gages may yield upwardly, 25 if necessary, during the pressure applying operation, the normal position of the gages, however, being determined by a stop screw 78 (Fig. 1) and a compression spring 80 which constantly urges the lower member of the group 40 against the stop screw. The gage mechanism may also be 30 adjusted longitudinally of the pad box by means of a slot 82 (Figs. 2 and 8) formed in the supporting plate 28, the mechanism being secured in adjusted position, however, during the operation of the machine by a thumb screw 84 passing through the slot 82 and threaded into a spacing block 86 and a slide 88 mounted thereon, these last-mentioned members supporting the members 40 and gage mechanisms carried 35 thereby and locating the gage mechanisms in a proper position heightwise of the pad box for operating on the heel ends of men's shoes.

The supporting plate 28 of the slide 26 has secured to its left-hand portion, as viewed in Figs. 1 and 8, a plate 90 which is shaped like the heel end of a large shoe in plan view and has an upstanding wall 94 adjacent to its edge which forms a heel shaped container for supporting a yieldable heel engaging pad 96, preferably formed 40 of solid but relatively resilient material such as rubber. The pad 96 is shaped at its left-hand end (Fig. 8) to join with the adjacent wall of the fluid filled pad 16 which underlies the forepart and shank portions of the shoe and sole 45 and, as shown in Figs. 8 and 10, the pad 96 extends above the wall 94 so that its exposed surface coincides substantially with the yieldable surface of the pad 16 when both pads are under pressure, this heightwise position of the pad 96 being determined by the position of the slide 26

which, as previously pointed out, is controlled by the adjusting screw 30. Overlying the top or sole and shoe supporting surfaces of the adjoining pads 16 and 96 is a flexible blanket or cover 98, preferably formed of resilient material such as rubber and forming a continuous unbroken surface for receiving the sole which is to be attached to the shoe bottom.

Extending downwardly from each side of the plate 90 is an ear 100 and in these ears is rotatably mounted a transverse shaft 102 having secured to its opposite ends by pins 104 (Figs. 1 and 10) a pair of upwardly extending arms 106. The upper ends of the arms 106 have pivotally connected thereto, by pins 108, a pair of substantially horizontal links 110 which, at their other ends are pivotally connected by pins 112 to a substantially heel shaped plate 114 which is flat on its lower surface (Fig. 8) and is cut away or cupped at its upper or operating surface 116 (as shown in Figs. 5, 8 and 10) to correspond substantially in shape to the concave surface of the attaching face of a heel or a heel base of the proper size and shape for the shoe on the pad. The plate 114 is preferably composed of metal such for example, as bronze and is rigid and non-yielding under pressure. The arrangement of the arms 106 and links 110 is such that the rigid heel conforming plate is superposed on the pads 16 and 96 and can ride or float 20 on the upper surfaces of the pads, as best illustrated in Fig. 8, so that when these surfaces are deformed under the sole attaching pressure applied by the machine, the rigid plate will be depressed heightwise of the shoe but will be returned to its initial position by the pads when the pressure on the shoe is relieved. The rigid plate 114, as shown in Figs. 5 and 8, is arranged to be interposed between the yielding surfaces of the pads 16 and 96 and the continuous flexible 25 cover 98 and may be located in such position lengthwise of the pad box that it will operate to conform or mold the heel seat portion of the sole to the shape of the attaching face of a heel while the sole and shoe are being pressed together 30 during the pressure applying operation, the sole at this time being in sufficient temper to permit its conformation under pressure. Since the flexible cover 98 rests on the concave surface of the conforming plate 114 it may and usually does 35 under continual use partake of or conform to the shape of this surface so that it ultimately becomes concave in shape even when no pressure is being applied to the sole and shoe.

It is desirable that the rigid sole conforming plate 114 be adjustable longitudinally of the pad to position it for operating on soles of different lengths. To this end the arm 103 at the front side of the pad, as viewed in Fig. 1, is provided with a forwardly projecting stud 118 (Figs. 1 and 7) rotatable in the arm and having an ear 120 (Fig. 10) in which is mounted a pin 122. Pivoted to this pin is a substantially horizontal link 124 pivotally connected at its other end by a pin 126 to an ear 128 rotatably mounted on an arm 130, which, in turn, is pivoted by a vertical pin 131 to a forwardly projecting plate 132 secured by screws 134 to the under side of the slide block 86. As shown in Figs. 3 and 10, the vertical pin 131 extends through the plate 132 and is held therein by a cotter pin, and a compression spring 136 is mounted between a head on the pin 131 and the arm 130 to hold the latter normally against the plate 132. Forwardly of the projection 128 the arm 130 carries a 40 45 50 55 60 65 70 75

downwardly extending indexing pin 138 (Fig. 10) which is arranged to enter any one of a series of holes 140 formed in the outer portion of the plate 132 on a radius struck from the center 131 and thus to adjust the plate 114 into proper positions longitudinally of the pad for operating on soles of different lengths. The arm 130 forms a handle whereby the upstanding arms 106 may be swung as a unit with their shaft 102 to adjust the heel conforming plate 114 forwardly and rearwardly of the pad box between the cover 98 and the upper surfaces of the adjoining pads 16 and 96. The pin 138 may be withdrawn from one of the holes 140 and inserted in another by moving the handle 130 manually against the compression spring 136.

The conforming plate 114 is provided at the opposite sides of its left-hand portion, as viewed in Figs. 1 and 10, with upwardly projecting lugs 142 having upper portions extending inwardly toward each other. These projections overlie the upper surface of the pad cover 98 just forwardly of, or toward the toe end of the pad relatively to, a pair of rectangular projections 144 (Figs. 6 and 9) formed on the opposite edge faces of the cover 98. The cover is thus maintained in substantial contact with the operating surface 116 of the sole conforming plate 114 by the overhanging lugs 142 and it is also prevented by the projections 144 from buckling or becoming loose longitudinally of the pad during the application of sole attaching pressure to successive soles and shoes.

As indicated above, the flexible cover 98 may tend under continual use to conform or shape itself to the concave operating surface of the rigid plate 114 so that the upper surface of the cover upon which the sole rests is likewise concave. The sole gages 50 and shoe gages 48 are carried by mechanism which, while it is capable of adjustment angularly with respect to the pad by reason of the pivot 76, spring 80 and adjusting screw 78 (Fig. 1), is not, as disclosed in the Better patent mentioned above, normally arranged to permit the sole gages to rest by gravity on the pad or to ride on the surface thereof during their operative movement toward or away from the opposite edge faces of the sole. Accordingly, in order to insure that the sole gages 50 will rest by gravity on the exposed surface of the flexible cover 98 and will ride along this surface during their operative movement, the sole gages have been constructed in the manner illustrated in Fig. 9 to permit the operating portions of the gages 50 to ride on the surface of the pad cover 98 and thus to be always in a position to engage the opposite edge faces of the sole. As shown in Fig. 9, the interconnected segmental portions 53 of the sole gages rest on, and are actuated by the transverse slide 44. These portions 53 are provided with laterally extending arms 148 which are bifurcated to form ears at their left-hand ends and have pivotally secured thereto, by pins 150, extensions or arms 152, the left-hand ends of which form the sole heel gages proper. This pivoted or hinged construction of each gage arm 148, 152 permits the operative ends of the sole gages to rest by gravity on the surface of the pad cover 98 and thus causes them to ride over this surface during their operative movement toward and away from the opposite edge faces of the sole. Accordingly, the gages will always engage and position the sole irrespective of its thickness and irrespective of the shape of the surface upon which the sole rests.

The cement sole attaching machine in which the pad box of the present invention is embodied is provided with abutments 154, 156 (Fig. 1) for engaging, respectively, the forepart of the shoe and the last in the shoe. These abutments are operated, as disclosed in the Ballard et al. patent, by substantially horizontal pressure applying levers 158 (Figs. 1 and 3) to apply the sole attaching pressure to the sole and shoe.

Although the operation of the mechanism embodying the present invention will be apparent from the foregoing description, a brief summary will be given for the purpose of clearness. The operator places a sole A on the pad cover 98 and depresses a gage operating treadle on the cement sole attaching machine to cause the combined forepart sole and shoe gages 22 and the heel end sole gages 152 to move into engagement with the opposite edge faces of the sole, the forepart gages merely finding the sole on the pad and becoming locked in operative position while the equally and oppositely movable heel sole gages move the heel end of the sole bodily relatively to the pad to locate it thereon. As stated above, the sole gages 152 ride on the concave or cupped surface of the pad cover 98 during their sole positioning movement. After positioning the heel end of the sole on the pad, the sole gages 152 become locked against movement away from the sole by reason of the roll and inclined slot arrangement 47 on the slide 44, as fully described in the Better patent referred to above. Since the sole A is thus located on the pad and is positively positioned longitudinally thereof, the operator can see where the heel seat portion of the sole is located with respect to the sole conforming plate 114. Consequently, he can, if necessary, adjust this plate lengthwise of the pad by the handle 130 until the plate is in a position to operate only upon the heel seat portion of a sole of the size mounted on the pad. During this adjustment the sole conforming plate slides readily between the pads 116 and 96 and the pad cover 98, and the pad cover is prevented from being displaced relatively to the sole conforming plate by the overhanging abutments 142.

The operator places a shoe B, assembled on a last C, on the sole, the forepart of the shoe being positioned relatively to the sole by the locked forepart gages 22. It will be understood, of course, that the inner or attaching surface of the sole, including its heel end, and the marginal portions of the entire shoe bottom have been previously treated with a suitable cement such, for example, as pyroxylin, and that this cement has been activated and is otherwise in condition to attach the sole permanently to the shoe bottom when pressure is applied to the sole and shoe.

The operator next swings the swinging frame member 68 forwardly into a substantially vertical position, as shown in Fig. 3, by the handle 70, thereby locating the shoe engaging abutments 154, 156 in position to engage respectively the forepart of the shoe and the top of the heel portion of the last C. He now depresses a pressure applying treadle on the machine to actuate the fluid pressure operated pressure applying mechanism thereon and to cause the levers 158 to move the abutments 154, 156 into engagement with the shoe and last and thereby to apply the sole attaching pressure. This action sinks the sole and shoe into the pad cover 98 and into the yieldable surfaces of the pads 16 and 96, thereby deforming these surfaces and depressing them heightwise of the shoe. Since the shoe conform-

ing plate 114 is connected by the pivoted links 110 to the adjusting arms 106, the plate is, of course, free to move heightwise of the shoe as the pad cover 98 and the surfaces of the pads are 5 deformed and depressed. Consequently, when the full pressure has been applied to the shoe and sole, the rigid conforming plate 114 molds or conforms the heel seat portion of the sole A to the shape of the attaching face of the heel which 10 is to be attached to the shoe, the molding taking place while the heel seat portion of the sole is being permanently attached to the shoe bottom by cement. At the same time, the portions of the sole A forwardly of the heel portion are being 15 cement attached to the shoe bottom under the pressure exerted against the sole by the forepart and shank portions of the pad. When the pressure on the shoe and sole is relieved as the pad is about to return to the operating station, in 20 the manner described in the Ballard et al. patent, the sole A including its heel seat portion will be permanently attached to the shoe bottom and this heel seat portion will also be molded or conformed by the rigid plate 114 so that it is substantially 25 complementary to the attaching face of a heel or a heel base.

It will be seen from the foregoing that the present invention not only provides for the permanent attachment of the heel portion of a sole 30 to a shoe bottom in such a manner that the edge portion of the sole is located in close fitting relation with the shoe bottom, but it also provides for simultaneously molding or conforming the heel seat portion of the sole to the shape of the 35 attaching face of a heel or heel base so that the latter may be applied to the sole by cement alone without having openings or spaces appear between the edges of the sole and the heel or heel base caused by an irregular or wavy edge on the heel portion of the sole. Since the sole conforming mechanism is adjustable for various sizes of shoes without disturbing either the pads or the sole and shoe positioning mechanism, the apparatus 40 is easy to operate. The convenience with which the heel conforming plate may be adjusted lengthwise of the pad and the accuracy with which this adjustment may be effected owing to the fact that the operator can see the longitudinal 45 position of the sole on the pad before he makes the adjustment, all tend to render the use 50 of the apparatus quick, economical and efficient.

Having thus described my invention, what I claim as new and desire to secure by Letters Patent of the United States is:

1. A machine for pressing soles on shoe bottoms having, in combination, a yieldable pad for receiving a sole and shoe, mechanism for effecting relative movement between the shoe and pad to press the sole against the shoe bottom, and rigid means yieldable with the pad for conforming the entire heel seat portion of the sole to fit the depression in the attaching face of a heel during the pressing operation.

2. A machine for pressing soles on shoe bottoms having, in combination, a pad for receiving a sole and shoe, a cover for said pad, mechanism for pressing the shoe and pad toward each other to press the sole against the shoe bottom, and separate means located between the pad and said cover for molding the heel portion of the sole to fit the depression in the attaching face of a heel or heel base.

3. A machine for pressing soles on shoe bottoms having, in combination, a pad having a yieldable surface thereon for supporting a sole

and shoe, a cover for said surface, mechanism for effecting relative movement between the shoe and pad heightwise of the shoe to press the sole against the shoe bottom, and rigid means located between the pad and said cover and movable heightwise with the pad and shoe for conforming the heel portion of the sole to the shape of the depression in the attaching face of a heel during the pressing operation.

4. A machine for pressing soles on shoe bottoms having, in combination, a yieldable pad for receiving a sole and shoe, a flexible cover for said pad, mechanism for pressing the shoe toward the pad to deform the latter and thereby to press the sole against the shoe bottom, and a rigid plate interposed between the pad and the cover and having a concave operating surface of substantially the same shape as the attaching face of a heel or heel base for conforming the heel seat portion of the sole to the shape of said attaching face during the pressing operation, said plate being free to move heightwise with the shoe as the pad is deformed under the pressure from the shoe.

5. A machine for pressing soles on shoe bottoms having, in combination, a yieldable pad for receiving a sole and shoe, mechanism for moving the shoe toward the pad to deform said pad and thereby to press the sole against the shoe bottom, a rigid plate supported by the pad and having a surface thereon for conforming the heel seat portion of the sole to the shape of the attaching face of a heel or heel base, and means for adjusting the plate relatively to the pad to adapt said plate for operating on shoes of different sizes.

6. A machine for pressing soles on shoe bottoms having, in combination, a yieldable pad for receiving a sole and shoe, a cover for said pad, mechanism for forcing the shoe toward the pad to deform the pad and thereby to press the sole and shoe together until the sole becomes attached to the shoe by cement, a rigid plate interposed between the pad and cover at the heel portion of the pad for shaping the heel seat portion of the sole, said plate having an operating surface corresponding in shape to the attaching face of a heel to be attached to the shoe, and means for adjusting said plate longitudinally of the pad between the pad and said cover to position the plate for operating on shoes of different lengths, said adjusting means being constructed and arranged to permit the plate to yield with the pad as the latter is deformed when the shoe is forced against it.

7. A machine for pressing soles on shoe bottoms having, in combination, a yieldable pad for receiving a sole and shoe, a flexible cover for said pad, mechanism for forcing the shoe toward the pad to deform the latter heightwise of the shoe and thereby apply sole attaching pressure to the sole and shoe, a rigid plate located between the heel portion of the pad and the cover, means for permitting the plate to be depressed heightwise with the pad when the pad is deformed by pressure from the shoe, and means for retaining the opposite side portions of the cover in engagement with the plate as the latter is depressed heightwise with the pad.

8. A machine for pressing soles on shoe bottoms having, in combination, a yieldable pad for receiving a sole and shoe, mechanism for forcing the shoe toward the pad to deform the pad heightwise of the shoe and thereby to apply sole attaching pressure to the sole and shoe, a rigid plate for conforming the heel seat portion

- of the sole to the shape of the attaching face of a heel or heel base, links connected to the opposite edge portions of said plate, arms connected to said links, said arms being arranged to swing simultaneously about a common axis, and means for swinging said arms predetermined distances about said axis to adjust the plate longitudinally of the pad to position said plate for operating on shoes of different lengths, said links permitting 5 the plate to move heightwise with the pad as it is deformed under the sole attaching pressure.
9. A machine for pressing soles on shoe bottoms having, in combination, a pad for receiving a sole and shoe, a flexible cover for said pad, 10 mechanism for pressing the sole and shoe toward each other thereby applying pressure to the sole and shoe, gages movable toward and away from the sole for positioning it relatively to the shoe bottom, a rigid plate between the pad and said 15 cover, said plate having a concave operating surface thereon for conforming a portion of the sole during the pressure applying operation, said flexible cover resting on said rigid plate, and means for causing said sole gages to rest by 20 gravity on said cover so that they will ride on the surface thereof during their movement toward the sole, thereby insuring that said gages will always contact with the sole when they are 25 operated to position it relatively to the shoe bottom.
10. A machine for pressing soles on shoe bottoms having, in combination, a yieldable pad for receiving a sole and shoe, a flexible cover for said pad, mechanism for pressing the shoe and 30 pad toward each other to apply sole attaching pressure to the sole and shoe, gages movable toward and away from the opposite edge faces of the sole for positioning the heel portion thereof relatively to the shoe bottom, a rigid plate interposed between the pad and its cover for conforming 35 the heel seat portion of the sole to the shape of the attaching face of a heel, said plate having a concave operating surface corresponding in shape to said attaching face, said flexible cover

resting on said plate and assuming the shape of its concave operating surface, and pivoted means for causing the operating ends of said sole gages to rest by gravity on said cover and to ride over the concave surface thereof during the movement of the gages toward the sole, thereby insuring that the gages will always engage the edge faces of the sole during their sole positioning movement.

11. A machine for pressing soles on shoe bottoms having, in combination, a pad having a yieldable surface for receiving a sole and shoe, a flexible cover for said pad, mechanism for pressing the shoe toward the pad thereby deforming said yieldable surface and applying pressure to the sole and shoe, shoe and sole positioning gages carried by gage arms and movable respectively toward and from the shoe and the opposite edge faces of the sole for positioning the shoe and sole relatively to each other on the pad, a rigid plate 20 interposed between the pad and said cover for molding the heel seat portion of the sole to the shape of the concave attaching face of a heel or plate base during the pressure applying operation, said plate having an operating surface 25 thereon corresponding in shape to said concave attaching face, said cover resting on said operating surface and conforming to the concave shape thereof, means for adjusting said plate longitudinally of the pad between it and the cover 30 to position the plate for operating on soles of different lengths, means for permitting said plate to move with the yieldable surface of the pad when the latter is deformed by pressure from the shoe, and means for causing the operating portions of the sole gages to rest of their own weight on the concave portion of said cover, thereby insuring that said gages will ride on said concave portion and will thus always engage the edge faces of the sole during their 35 sole positioning movement, said means comprising hinges provided on the arms carrying said sole gages.

CHARLES H. PEPIN.

CERTIFICATE OF CORRECTION.

Patent No. 2,158,196.

May 16, 1939.

CHARLES H. PEPIN.

It is hereby certified that error appears in the printed specification of the above numbered patent requiring correction as follows: Page 6, second column, line 2 $\frac{1}{2}$, claim 11, for the word "plate" read heel; and that the said Letters Patent should be read with this correction therein that the same may conform to the record of the case in the Patent Office.

Signed and sealed this 9th day of April, A. D. 1940.

(Seal)

Henry Van Arsdale,
Acting Commissioner of Patents.
